ADJUSTABLE EMERGENCY LIGHTING FIXTURE

Richard H. Darling, Fairfield, and Paul O. Rawson,
Easton, Conn., assignors to Dual-Lite Company, New-
ton, Conn.

Filed Sept. 25, 1972, Ser. No. 291,981

Term of patent 14 years

Int. Cl. D26—03

U.S. Cl. D48—20 K

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top view of an adjustable emergency lighting fixture showing our new design;

FIG. 2 is a side view thereof;

FIG. 3 is a front view thereof;

FIG. 4 is a rear view thereof;

FIG. 5 is a bottom view thereof;

FIG. 6 is a view of the side opposite that shown in FIG. 2;

FIG. 7 is a top view of a second embodiment of our new design;

FIG. 8 is a side view thereof;

FIG. 9 is a front view thereof;

FIG. 10 is a rear view thereof;

FIG. 11 is a bottom view thereof; and

FIG. 12 is a view of the side opposite that shown in FIG. 8.

We claim:

The ornamental design for an adjustable emergency lighting fixture, substantially as shown and described.
